CLAIM

The ornamental design for a bicycle freewheel gear
cover, as shown and described.

DESCRIPTION

FIG. 1 is a top, side and front perspective view of a
bicycle freewheel cover showing my new design, it
being understood that the broken lines are for illustra-
tive purposes only and form no part of the claimed
design;

FIG. 2 is a side elevational view thereof, the opposite
side being a mirror image of that shown;

FIG. 3 is a bottom plan view thereof in open condition;
and

FIG. 4 is a top plan view thereof in closed condition.
